SPARK PLUG CONSTRUCTION

Addison C. Hoof, Hinsdale, Ill.

Application February 19, 1935, Serial No. 7,230

8 Claims. (Cl. 123—169)

My invention relates to improvements in spark plugs and like devices.

My invention relates more particularly to improvements in the construction of spark plugs for internal combustion engines such as are used in automobiles, aeroplanes and motor boats.

One of the objects of my invention is to produce a new and useful element of a spark plug, consisting of a self-contained conductor and surrounding insulating medium, which is highly refractory and capable of withstanding the effects of excessive temperatures such as are produced within the cylinders of gas engines.

Another object of my invention is to produce an element of the character described, in which the insulating medium is composed of basalt or other igneous rock; a substance possessing high specific resistance to the passage of the electric current, although hot, and which yields to manipulation only when submitted to temperature much higher than that ever attained within the cylinder of an internal combustion engine.

A further object of the invention is to provide an insulator having practically the same coefficient of expansion as the metal conductor so that cracking of the insulator due to changes in temperature will be avoided.

During recent years an extensive investigation has been made to determine whether or not castings could be made from basalt or other igneous rocks. This investigation covered a development whereby an igneous rock may be melted, cast to desired shape, and by proper heat treatment devitrified, to form a material possessing good electrical insulation qualities and high mechanical strength.

Various objects of cast basalt such as building cornices, corner stones and paving blocks, have been made in England and France, using some form of a devitrifying process since 1700, and stone bottles since as early as 1600.

Basalt is a form of igneous rock widely distributed on the earth's surface, heavy, dark colored, hard, and very fine grained. It is not a mineral of definite constitution, but a mixture of several, generally labradorite, augite, olivine and magnetite.

Basalt melts between 1200 and 1400 degrees C. and may be poured into a mold. If allowed to cool rapidly it becomes a jet black glass quite similar to obsidian, very brittle and subject to high internal stresses. With several hours heat treatment at 800 to 1000 degrees C. a casting devitrifies into a tough material showing a fracture of very much the same appearance as the orig-

inal rock. It has a good electrical resistance and ability to endure severe mechanical shock.

An igneous rock is a solidification of molten matter from within the earth, as contrasted with a sedimentary rock which is a geologically deposited material. Basalt is igneous and belongs to the salemite group. It is close grained. The grains are too small to be readily distinguished by the eye but may contain larger grains of certain minerals interspersed in the dense material; that is, it may be porphyritic.

Gabbro and diabase are much the same as basalt, but somewhat coarser, so that grains of the constituent minerals are distinguishable to the unaided eye. Gabbro is noticeably granitoid. In the molten form gabbro and diabase are so nearly identical with basalt that either of them may be used since it is only necessary to adjust the heat treatment to control the mineral constituents formed during the devitrifying cycle. Hence it is only necessary to determine the proper heat treatment to give the particular crystallization desired, the same crystallization being obtained from either of the three forms of raw material.

It has been found by experiment that when basalt is used as an insulator that when an arc punctures the basalt partially fuses together or heals so that with a repeated arc it will puncture along a new path, whereas porcelain, once punctured, will always flash through the same path.

The coefficient of expansion of basalt is practically the same as iron, so that it may be cast around steel fittings with good bonding. Basalt may be made to wet steel and does not require to be cemented to the insulator fittings as does porcelain, quartz, or glass. As a result there is no tendency for steel fittings, even under unusual heats, to work loose in basalt insulators or give any trouble such as is likely to occur with porcelain, quartz, or glass.

Accordingly, the present invention relates to the use of basalt or similar materials in connection with an improved spark plug as hereinbefore explained.

Other objects and advantages thereof will be more apparent from the following description wherein several embodiments of the invention are illustrated.

In the drawing, Fig. 1 is a vertical sectional view of one form of my improved spark plug;

Fig. 2 is a cross-sectional view thereof taken generally on the line 2—2 of Fig. 1;

Fig. 3 is a similar vertical sectional view of a modified form of the invention, and

Fig. 4 is an elevational view of the basalt insulator shown in Fig. 3.

5 Referring to Fig. 1, I have shown a spark plug which includes a casing or shell 10 formed with the hexagonal exterior walls 12 for easy manipulation to mount the same in a suitable tapped opening of an internal combustion engine. The 10 lower portion of the shell 10 may be reduced and screw threaded as shown in 14. The shell may have a body bore 16, a tapered wall portion 18 and reduced bore 20.

The insulator B may be formed of basalt or 15 other igneous rock as previously described, and may comprise the enlarged body portion 22 and reduced upper and lower extremities 24 and 26. The body portion 22 may be formed with the 20 tapered walls 28 and 30. A metallic conductor 32 having the protruding shaft portion 34 and the firing tip 36 is adapted to be cast integral with the insulator B as will now be explained.

In the form of the invention thus far described, I contemplate the placing of the shell 10 and the 25 conductor 32 into a mold so constructed that molten basalt at proper melting temperature may be poured into the mold and take the shape shown in the drawing. In this manner an efficient one-piece spark plug has been provided 30 with an insulator having the same co-efficient of expansion as the shell 10 and the conductor 32. As thus constructed the spark plug has no joints which it is necessary to seal and loss of compression in an internal combustion engine due to 35 cracked or broken insulators as previously explained will be an impossibility.

In the form of the invention shown in Figs. 3 and 4, I again cast an insulator B in the shape shown and provide the conductor 32 positioned 40 in the mold so that the insulator and conductor are cast integral. The shell 10 may be generally similar to the one previously described, except that it is provided with an internal threaded bore 40 adjacent its upper end to receive a retainer nut 42 in the usual form to securely hold the insulator B against the tapered shoulders 18. With this construction it will be obvious that 45 the spark plug can be made in the usual three pieces as is common in the art.

50 While I have shown and described a specific form of my invention and one modified form thereof, it will be obvious to those skilled in the art that many and varied changes may be made in the particular form thereof. The generic idea of the invention is the provision of an insulator

for spark plugs or similar devices constructed of basalt or other igneous rock material, and I do not wish to be limited in any particular, rather what I desire to secure and protect by Letters Patent of the United States is:

5 1. A spark plug having a metal shell, a basalt insulator and a metal conductor mounted in said insulator.

10 2. A spark plug having a metal shell, a basalt insulator and a metal conductor mounted in said 10 insulator, said insulator adapted to be molded around said conductor.

15 3. A spark plug comprising an elongated insulator of basalt, a conductor extending longitudinally through said insulator, a casing for said 15 insulator and means for making a gas tight seal between said insulator and said casing.

20 4. A spark plug for internal combustion engines comprising a metal shell, elongated insulating means therein consisting essentially of a basalt 20 material, a conductor therein having at one end a shaft, at the opposite end a firing tip and means including a retaining nut member for effectively sealing said insulator in said casing.

25 5. A spark plug comprising an elongated insulator of basalt, a conductor extending longitudinally through said insulator, a casing for said 25 insulator and means comprising a retainer nut member frictionally engaging said casing and bearing against a shoulder on said insulator for 30 making a gas tight seal between said insulator and said casing.

35 6. A spark plug comprising an elongated insulator of basalt, said insulator formed with an enlarged body portion, tapered upper and lower 35 walls thereon and reduced cylindrical extremities extending therefrom, a conductor extending longitudinally through said insulator, a casing for said insulator, said casing having a tapered ledge upon which the lower wall of said insulator body 40 portion rests and means for making a gas tight seal between said insulator and said casing.

45 7. A spark plug comprising a basalt insulator member, a conductor in the form of a metal rod passing longitudinally therethrough and a shell 45 member for mounting said spark plug on an internal combustion motor adapted to be cast integral with said insulator.

50 8. A spark plug comprising a basalt insulator member, a conductor in the form of a metal rod 50 passing longitudinally therethrough and a shell member for mounting said spark plug on an internal combustion motor, said shell and conductor adapted to be held in a mold and said basalt in a molten condition cast integral therewith.

55 ADDISON C. HOOF.
